UNITED STATES PATENT OFFICE

SIDNEY G. HERZOG, OF SAN FRANCISCO, CALIFORNIA, ASSIGNOR TO FOSTER & KLEISER COMPANY, OF SAN FRANCISCO, CALIFORNIA, A CORPORATION OF NEVADA

DESIGN FOR AN ADVERTISING SIGN

Application filed February 25, 1931. Serial No. 38,826. Term of patent 3½ years.

To all whom it may concern:

Be it known that I, SIDNEY G. HERZOG, a citizen of the United States, residing at the city and county of San Francisco and State of California, have invented a new, original, and ornamental Design for an Advertising Sign, of which the following is a specification, reference being had to the accompanying drawings, forming part thereof.

Fig. 1 is a front elevation of a sign showing my new design.

Fig. 2 is a plan view of the sign.

I claim:

The ornamental design for an advertising sign substantially as shown.

SIDNEY G. HERZOG.
